UNITED STATES PATENT OFFICE

PETER ESSER, OF CLIFTON, NEW JERSEY, ASSIGNOR TO TAKE-A-TOY, INC., OF NEW YORK, N. Y., A CORPORATION OF NEW YORK

TOY

Application filed February 21, 1929. Serial No. 341,779.

One of the objects of my invention is to provide a toy which is of simple and inexpensive construction, and capable of operating automatically in an amusing and unexpected manner.

Another object of the invention is to provide a toy of the vehicle type which in operation closely simulates a boy coasting on a sled.

10 A still further object of the invention is to provide a novel and improved toy.

These and other objects of my invention and features whereby they may be attained will be clearly understood from the following description and accompanying drawings, in which:

Figure 1 is a plan view, partly in section, of a toy embodying the features of the invention in their preferred form, the toy being shown in operating condition and two positions of parts of the toy being shown, one by full lines and the other by broken lines;

20 Figs. 2 and 3 are respectively front and rear-end views of the toy with a figure or doll shown in Fig. 1 removed;

Fig. 4 is a side view, partly in section, of the toy as illustrated in Fig. 1; and

Fig. 5 is a view corresponding to Fig. 4 but on a reduced scale and showing the toy 30 in another position of operation.

My improved toy as illustrated in the drawings is provided with a frame or body in the form of a sled having runners 2 and a top 4. Instead of the sled being supported by the runners, however, it is supported on four disks or wheels 6 arranged at the inner sides of the runners. The rear wheels 6 are carried by an axle shaft 8 and the front wheels are mounted on an axle shaft 10.

0 The toy vehicle is adapted to be propelled by means of a spring motor consisting of a spiral spring 12 which has its inner end secured to a winding shaft 14 and its other end secured to a gear 16 loosely mounted on the winding shaft 14. The gear 16 operatively engages a pinion 18 secured on the axle shaft 8 so as to drive the shaft during the unwinding of the spring. The necessary drag is placed on the spring motor by means of suitable gearing comprising gears 20. The

spring motor is adapted to be wound by means of the usual thumb nut 22 secured on one end of the winding shaft.

The front axle shaft 10 is mounted in the lower ends of depending arms 22 having their upper ends secured to a cross bar 24 centrally pivoted on the top of the body of the sled, this cross bar having the appearance of the usual steering bar on certain types of sleds.

During the travel of the toy, the front axle is turned in opposite directions alternately so as to cause the front wheels to take a more or less of a sinuous course. This is accomplished through a rod 25 having one end pivotally connected with one of the depending arms 22 and its other end pivotally connected with a crank disk 26 secured on the inner end of the motor shaft 14.

A boy doll which is adapted to ride on the sled, has its body made in two parts that are pivotally connected by a rivet 28 near the waistline of the doll so as to permit sidewise movements of said parts. The lower part of the body of the doll, at a distance below the waistline, is provided with a socket 30 for receiving a pivot pin 32 which projects upwardly through a clearance hole in a boss 34 on the top of the sled. The arms of the doll are pivotally mounted at the shoulder on a pin 36 which extends through an aperture in the body of the doll, the aperture being considerably wider than the diameter of the pin. The hands of the doll are provided with holes or sockets for receiving upstanding pins 38 on the end portions of the steering bar 24.

With this construction it will be apparent that as the toy is propelled along by its spring motor and the front wheels turned first in one and then in the other direction, the connections of the steering bar 24 with the loosely hinged arms of the doll, the pivotal connection between the two parts of the body of the doll, and the pivotal mounting of the lower body part of the doll upon the pin 32, all cooperate to cause movements of the entire body of the doll in close simulation to a boy coasting on a sled and moving his body to steer the sled by means of the usual steering bar.

In the illustrated construction, means is also provided whereby when the sled has traveled a predetermined distance, the doll is suddenly thrown upwardly and forwardly from the sled in such a manner that it makes one or more somersaults in the air before falling to the ground. To provide for this a trap plate 40 is mounted on the top of the sled and extends from a point substantially beneath the shoulders of the doll to the rear end of the top of the sled. The forward end of the plate is hinged at 41 to the top of the sled. When the plate is swung down on the top of the sled it holds a coiled spring 42 under compression. This spring is arranged in an upwardly opening socket 43 depending from the top of the sled, and has its upper end secured to the underside of the trap plate and its lower end secured to the bottom of the socket. The plate is held down to tension the spring by means of a trigger 44 centrally pivoted on a rearwardly extending bracket 45 on the rear end of the frame of the toy. The upper end of this trigger 25 is provided with a head or shoulder which, when set in holding engagement with the top side of the rear end of the trap plate, is held in position by means of a spring 46 having one end engaging the lower end of the trigger and its other end engaging a fixed portion 30 of the frame.

The lower end of the trigger is provided with a horizontal aperture through which a cord 48 extends. This cord has one end secured to the motor shaft 14 so that the cord will be wound on the shaft as the spring is unwound during the travel of the toy. Two stops 50 and 51 are adjustably provided on the cord at the rear of the trigger, the smaller 40 stop 50 being positioned a distance in advance of the other stop and being formed by a knot in the cord.

When the toy has traveled a predetermined distance the stop 50 is carried by the winding cord into engagement with the lower end of the trigger to release the trigger from the trap plate, whereupon the plate is suddenly swung upwardly by means of its spring which throws the doll forwardly and upwardly and causes it to make one or more somersaults before falling to the ground. The stop 50 is of such diameter that it will pass through the hole in the trigger under the pull of the motor shaft, but in doing so it frictionally engages the wall of the hole sufficiently to release the trigger. At a predetermined distance of travel after the trigger has been thus released, however, the larger stop 51 strikes against the lower end of the trigger to prevent further unwinding of the spring, thus stopping the travel of the toy.

To re-set the toy, the trap plate is swung down on the top of the sled and held by the trigger. The doll is then mounted as described and the spring wound, the winding

of the spring unwinding the cord from the spring shaft ready for the next operation.

As will be evident to those skilled in the art, my invention permits various modifications without departing from the spirit thereof or the scope of the appended claims.

What I claim is:

1. A toy having, in combination, a vehicle, means for propelling the vehicle, a doll mounted on the vehicle, means carried by the vehicle acting automatically after a predetermined distance of travel of the vehicle to throw the doll from the vehicle and means carried by the vehicle for controlling the time of operation of said automatically acting means.

2. A toy having, in combination, a vehicle, means comprising a spring motor for propelling the vehicle, a doll mounted on the vehicle, and means acting automatically after a predetermined distance of travel of the vehicle to throw the doll from the vehicle, comprising a supporting member hinged at its forward end on the vehicle beneath said doll, a spring tending to throw said supporting member upwardly, a trigger for holding down said supporting member against the tension of said spring, and means actuated by said spring motor after a predetermined distance of travel of the vehicle for releasing said trigger from the supporting member, and means carried by the vehicle for controlling the time of operation of said automatically acting means.

3. A toy having, in combination, a vehicle, means comprising a spring motor for propelling the vehicle, a doll mounted on the vehicle, and means acting automatically after a predetermined distance of travel of the vehicle for throwing the doll from the vehicle, comprising a supporting member hinged at its forward end on the vehicle beneath said doll, a spring tending to throw said supporting member upwardly, a trigger for holding down said supporting member against the tension of said spring, and means actuated by said spring motor after a predetermined distance of travel of the vehicle for releasing said trigger from the supporting member, comprising a cord connected with the motor shaft so as to be wound thereon during the travel of the vehicle, and means comprising an abutment carried by the cord and arranged to engage and release the trigger when a predetermined length thereof has been wound on said shaft.

4. A toy having, in combination, a vehicle, a doll mounted on the vehicle, and means for throwing the doll forwardly from the vehicle at a predetermined point in the travel of the vehicle and for stopping the vehicle at the end of a predetermined distance of travel thereafter.

5. A toy having, in combination, a vehicle, means comprising a spring motor for pro-

propelling the vehicle, a steering device at the front of the vehicle adapted to be turned alternately in opposite directions during the travel of the vehicle, said device comprising
5 a bar extending across and centrally pivoted on the top of the vehicle, connections between said device and the spring motor for thus turning said device, a doll mounted on the vehicle having its body made in two parts
0 pivotally connected near the waistline, the doll being positioned face down on the top of the vehicle, a detachably pivotal connection between the lower part of the doll body and the top of the vehicle to permit the lower
5 body part to be turned about a vertical axis, arms on the doll having their shoulder ends pivotally connected to the upper part of the doll body, and means for detachably and pivotally connecting the hands of the doll with
0 the ends of said cross bar.

6. A toy having, in combination, a vehicle, means comprising a spring motor for propelling the vehicle, a steering device at the front of the vehicle adapted to be turned
5 alternately in opposite directions comprising a bar extending across and centrally pivoted on the top of the vehicle, a doll detachably mounted face downward on the top of the vehicle with the arms of the doll pivotally connected at the shoulders to the doll, and means for detachably and pivotally connecting the outer ends of the arms of the doll to the end portions of said cross bar.

7. A toy comprising a vehicle, means for propelling the vehicle comprising a spring motor, means comprising a cord acting when pulled outwardly to wind up the spring of the motor and when released to permit the spring to unwind to propel the vehicle, the cord being wound up during the travel of the vehicle, a pivotally mounted trap member, a spring tending to swing the trap member in one direction, and a trigger for holding the trap member in position against the tension of said spring, said cord having provision of means for releasing said trigger from the trap member when a definite length portion of the cord has been wound up during the travel of the vehicle.

9. In testimony whereof, I have signed my name to this specification this 20th day of February, 1929.

PETER ESSER.
